(57) **CLAIM**

The ornamental design for an indicator window for a display support, as shown and described.

DESCRIPTION

FIG. 1 is a perspective view of a first embodiment of an indicator window for a display support, shown in the environment of use;

FIG. 2 is a top plan view thereof;

FIG. 3 is an enlarged top plan view thereof, taken from FIG. 2;

FIG. 4 is a perspective view of a second embodiment of an indicator window for a display support, shown in an environment of use;

FIG. 5 is a top plan view thereof; and,

FIG. 6 is an enlarged top plan view thereof, taken from FIG. 5.

The broken lines illustrating the monitor and support arm in FIGS. 1-6 are environment, and the remaining broken lines in FIGS. 1-6 illustrate portions of the indicator window for a display support that form no part of the claimed design.
